DESIGN FOR A COMBINATION DISPLAY FIXTURE AND STORAGE CASE

Hans O. Shults, Chicago, Ill.

Application June 23, 1934, Serial No. 52,301

Term of patent 7 years

To all whom it may concern:

Be it known that I, HANS O. SHULTS, a citizen of the United States, residing at Chicago, in the county of Cook and State of Illinois, have invented a certain new, original, and ornamental Design for Combination Display Fixture and Storage Case, of which the following is a specification, reference being had to the accompanying drawing, wherein

Fig. 1 is a perspective view of the article, showing my new design;

Fig. 2 is a side view of the same; and

Fig. 3 is a plan view.

I claim:

The ornamental design for a combination display fixture and storage case substantially as shown.

HANS O. SHULTS.
